(57) **CLAIM**

The ornamental design for a candle light holder, as shown and described.

DESCRIPTION

FIG. 1 is a front side perspective view of a candle light holder showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The bottom of the candle light holder forms no part of the claimed design and is therefore omitted.
